PICTURE FRAME STRUCTURE

Robert Stern, Chicago, Ill.

Application April 13, 1934, Serial No. 720,432

5 Claims. (Cl. 40—152)

This invention relates to framing structures and more particularly to picture frames and the like peculiarly designed to reduce the cost of material and labor in their construction and to increase their general efficiency.

Heretofore the usual method of framing pictures has been to make a frame having a single comparatively deep rabbet or groove around the inner edge of the molding to receive a glass and picture. A suitable picture backing, which is usually of cardboard, is then laid in this rabbet over the picture, and nails or brads are driven into the side wall of the rabbeted groove to hold the backing, picture, and glass in place. Such a method presents a number of objections in that the structure is unsightly, the nails interfere with the dusting and cleaning of the back, and the backing is usually insufficiently supported by the brads and permits the picture to buckle or wrinkle to a greater or less extent, and the driving of the nails or brads requires considerable time and skill and adds materially to the expense.

In some cases a paper sheet is placed over the entire back and secured by gluing the edges to the back of the picture molding. However, this paper sheet is necessarily spaced from the picture backing to provide room for the nails therebetween and the paper is easily torn and great care must be used in handling the completed structure.

The present invention successfully overcomes the above noted objections to prior structures and presents many new and novel advantages.

The present invention not only reduces the expense of manufacture and enables the device to be assembled by automatic machinery, but also provides a much more rigid structure with a smooth dustproof backing over the entire device which cannot be punctured or torn in ordinary use.

Among the important features of this invention are the facilitation of assembly operations resulting in a definite increase in production; increased stability and positive frame support is made possible; a reduction in weight of the complete framed structure is provided by a reduction in the thickness of the frame molding; and a generous saving in raw material is effected thereby. The improvements incorporated in a structure made in accordance with the present invention materially increase the sales value of the product.

The finished product provides a completely sealed rigid unit having a smooth, flush, dustproof back and eliminates all air space between the component parts. The appearance of the finished product is greatly improved and a more

valuable item may be manufactured at a low cost. A further object is the provision of a structure which may be easily and cheaply assembled by unskilled labor without the use of hammer and nails adjacent the glass, thereby substantially eliminating all breakage of glass.

It is also an object to provide a framed structure which will be cheap to manufacture, easy to assemble and more rigid after assembly than the usual framed structure. The structure is particularly adapted for quantity production and may be easily and efficiently assembled by the use of automatic machinery when desired.

It is an object to provide a picture frame structure in which the glass and picture may be permanently and rigidly secured therein, and in which the entire back of the structure may be completely closed and made dustproof in a manner to materially strengthen the entire device and to prevent tearing or rupturing of the backing sheet.

The invention also provides a structure which may be stacked or stored one on top of the other in a compact manner without material injury to any of the parts.

Further objects and advantages will be apparent from the specifications and the appended claims.

In the drawing:

Figure 1 is a perspective view in transverse section through a picture frame structure and illustrates one embodiment of the invention.

Fig. 2 is a fragmentary perspective view of the back of the structure illustrated in Fig. 1, with a portion of the paper backing raised for purposes of illustration.

Fig. 3 is a transverse section through one of the side pieces or moldings.

Referring to the drawing in detail, the embodiment illustrated comprises a rectangular picture frame which may be made up of side pieces 1 and similar end pieces. For purposes of this disclosure, the term "side pieces" is intended as a broad term covering end pieces as well, which are used to make up the usual frame. It will, of course, be understood that shapes other than rectangular may be made if desired without departing from the spirit of the invention.

The side and end pieces 1 comprise the usual comparatively narrow moldings having an inner groove or rabbet 2 providing a step or shoulder 3 limiting the size of a glass and picture or other suitable display object to be supported therein. A second groove or rabbet 4 is arranged to receive a suitable picture backing and provides a second step or shoulder 5 limiting the size of the picture.

backing. These two grooves provide what may be called a stepped recess extending around the inner back edge of the frame. A glass 6 or other suitable sheet of transparent material is seated in 5 the groove 2 and the picture or other object 7 to be displayed through the glass is supported thereon. The glass and picture are preferably of the same size and fit snugly in the groove 2, and their combined thickness is the same as the height of the 10 step or shoulder 3 whereby the back of the picture is flush with the floor of the second rabbet or groove 4. The glass may be dispensed with if desired but in any case the groove 2 is completely filled by the picture or display object so that it is 15 flush with the floor of the groove 4.

After the glass and picture have been inserted in the frame, a picture backing sheet 8, which is preferably of semi-rigid material such as straw board or cardboard, is inserted in the second 20 rabbet or groove 4 for retaining the glass and picture in position.

The picture backing 8 is of substantially the same thickness as the height of the shoulder 5 thereby bringing the surface flush with the back 25 of the frame molding. The picture backing member 8 is preferably secured in place by suitable staples 9 extending therethrough and into the frame molding as illustrated, and, as the picture backing material 8 may be comparatively soft, the 30 staples or other suitable fasteners may be pressed into the material in such a manner that they do not extend materially above the surface of the backing 8. The staples 9 are preferably spaced around the frame substantially as indicated in 35 Fig. 2, and the structure then presents a framed picture having a smooth flush back.

The frames are usually made up of four or 40 more mitered or beveled strips of molding and may be secured together at the corners by suitable nails or brads 10. A sheet 11 of comparatively thin paper is then glued over the entire back of 45 the structure adhering to the entire surface of the picture backing 8 and to the exposed portions of the frame moldings 1. By this method a very rigid structure may be easily and quickly assembled and all of the parts will be securely held 50 together in such a manner that the frame cannot become loosened; the mitered joints are held snugly together without glue; and the glass and picture will be snugly secured in place.

In the usual picture frame structure a single 55 deep rabbet is commonly used and the glass and picture are inserted therein and then secured by brads. The rabbet must be sufficiently deep to allow the brads or nails to be driven into the side 60 wall of the rabbet molding, and it is common practice to then apply glue to the exposed back surface of the molding and secure a sheet of paper over 65 the entire back. However, this paper is only secured to a comparatively small surface of the molding, and there is a considerable air space between the picture and the paper backing in 70 which the nails are enclosed. The paper backing, therefore, is easily torn, and, in any case, adds very little to the strength and rigidity of the 75 structure.

In such usual structures substantially the entire assembly is held together by nails at the 80 corners of the frame similar to the nail 10 illustrated in Fig. 2 and it is usually necessary to use several nails in each corner and to glue the mitered surfaces if a rigid frame is desired.

In the present structure one nail at each corner 85 is entirely sufficient and even that may be dispensed with if desired as the picture backing 8,

which is securely stapled to all of the side pieces, secures the entire frame together and this backing is further secured to the frame by means of a paper or other fabric backing sheet 11 secured to 90 the entire surface of the picture backing 8 and to the exposed surface of the frame, thereby preventing racking of the frame and rigidly holding all of the parts, including the mitered or beveled corners of the molding, in place.

As previously stated, it is a particular object of 95 the invention to provide a device which may be assembled more or less completely by automatic machinery, and in assembling the structure disclosed herein, it is only necessary to secure the side pieces together to form a frame either by 100 clamping them together or securing the corners by nails as described, and the glass 6, the picture 105 7, and the backing 8 may then be laid in position and the frame may be passed through a stapling machine whereby the staples 9 are quickly and accurately driven into position to secure all of the parts together. Staples, such as disclosed in 110 the drawing, are preferable for securing the picture backing. However, other types of suitable fasteners may be used if desired.

The assembled device may then be passed 115 through a gluing machine whereby the entire back surface including the picture backing 8 and the exposed back surface of the molding will receive a coating of glue, and the paper sheet 11 120 may then be applied snugly over the entire surface. However, if desired, the paper or fabric sheet 11 may first receive a coating of glue and then be applied to the back of the structure.

In the past it has been common practice to 125 apply glue to the exposed back surface of the frame, which surface was considerably higher than the usual picture backing in order to provide room for the retaining nails or brads. The glue was applied around the surface of the frame 130 by hand, and the sheet was then applied thereto. However, this slow and uncertain method causes more or less glue to be applied to, or run down on, the side of the molding and it is therefore necessary to clean each frame after the paper is applied. Also, if the frames are then stacked in a 135 pile, it is necessary that this should be done carefully and accurately in order to prevent tearing or puncturing the unsupported paper backing.

In the manufacture of picture frame structures, the most common method in use at the 140 present time employs brads or nails which are driven into the side of the frame molding and overlapping the picture backing to prevent the glass and picture and backing from falling out of 145 the frame. These nails are driven in with a hand hammer, and, excepting in cases where the operator is thoroughly experienced, this operation is extremely slow. Also, the nails are driven at various angles and therefore do not provide uniform support to all sections of the glass inside the frame. There is, therefore, considerable breakage of glass because of uneven pressure of the nails when the hand tacking compresses the 150 glass and picture backing against the frame molding.

In the instant invention the pressure on the glass is uniform throughout and breakage is substantially completely eliminated. Also, in previous methods of manufacturing and assembling 155 substantially the entire structure is held together by the nails in the mitered ends of the frame molding. Such structures have a natural tendency to warp. With the method disclosed herein, the picture backing 8, which is secured to the

frame molding by means of staples 9, becomes substantially an integral part of the entire structure, and this, together with the fabric backing 11, which is secured over its entire surface to the 5 picture backing and frame, acts as an efficient warp preventive.

In some cases it is desirable to manufacture round, oval or other shaped frames in which the molding is made up of any desired number of 10 parts, and in which it may be difficult to nail the ends of the molding together. This invention is well adapted for such structures in that the pieces of molding will be rigidly held together to form a frame whether the ends of the molding 15 are secured together or not. It is also sometimes desired to make frames, particularly round or oval ones, in which the entire frame is carved from an integral unit. In such cases the recesses may be formed on a suitable carving or rabbeting 20 machine, or by hand as desired.

As a result of the savings which are effected by the present invention, it is possible to increase the size of the complete unit without adding to the cost of manufacture, which additional cost 25 was necessary under previous methods. This saving materially increases the dealer and consumer interest as the net result is a general saving in the cost of the same size item over the previous method of manufacturing, and these 30 savings may be passed on to the dealer and through him to the ultimate consumer.

Modifications may be made by those skilled in the art without departing from the spirit of the invention, and it is therefore, desired that the 35 invention be limited only by the prior art and the scope of the appended claims.

Having thus described this invention, what is claimed and desired to be secured by Letters Patent is:

40 1. A rigid, unitary, framed structure of the character described comprising associated moldings positioned to form a frame, each molding having a stepped recess forming two grooves in its inner back edge, a display object in the first 45 groove adjacent the edge and having its back surface substantially flush with the floor of the second groove, a backing member in intimate contact with and overlapping said display object and attached to the floor of the second groove 50 and having its back surface substantially flush with the back surface of said molding, and securing means for said backing member comprising staples substantially flush with the back surface thereof and extending through said backing member and into the floor of said second step.

55 2. A rigid, unitary, framed structure of the character described comprising associated moldings positioned to form a frame, each molding having a stepped recess forming two grooves in its inner back edge, a display object in the first groove adjacent the edge and having its back surface substantially flush with the floor

of the second groove, a cellulosic member in intimate contact with and overlapping said display object and supported on the floor of the second groove and having its back surface substantially flush with the back surface of said molding, securing means for said backing member extending through said backing member and into the floor of said second step and pressed into said board to provide a substantially flat back, and a fabric sheet cemented to the exposed back, surface of said molding and to a substantial portion of the surface of said backing member.

80 3. A picture frame structure of the character described comprising a surrounding molding having a stepped recess around its inner edge, said recess forming a first groove adjacent the edge to receive a glass and picture, the back of said picture being substantially flush with the floor of said second step, and a second groove extending outwardly beyond said first step to receive a picture backing substantially flush with the back surface of said molding, spaced staples securing said picture backing to the floor of said second groove to provide a substantially rigid frame structure, and a sheet of fabric cemented 85 to the entire exposed rear surface of said molding and to said picture backing.

90 4. A picture frame structure of the character described comprising abutting side pieces forming a frame having a stepped recess around its inner back edge forming a first groove adjacent the inner edge and a second groove remote from the inner edge, a display object supported in said first groove and having its back surface substantially flush with the floor of said second groove, a backing member supported in said second groove, spaced staples extending through said backing member and into the floor of said second groove beyond the edge of said display object to retain all of the parts assembled in a 100 substantially rigid structure, and a relatively thin fabric glued to the exposed surface of the side pieces and to the adjacent surface of the backing member.

105 5. A picture frame structure of the character described comprising comparatively thin moldings positioned to form a frame, said frame having an inner groove and an outer groove, a glass in said inner groove, a picture in said inner groove and substantially the same size as said 110 glass and in surface contact therewith, said glass and said picture completely filling said groove, a picture backing board in surface contact with said picture and extending beyond the edge thereof to completely fill said second groove, securing means for said board comprising staple-like fasteners securing said board to the floor of said second groove to provide a rigid structure 115 having a substantially smooth and flat back surface, and a fabric glued over the entire back surface of the structure.

120 ROBERT STERN.

CERTIFICATE OF CORRECTION.

Patent No. 1,971,923.

August 28, 1934.

ROBERT STERN.

It is hereby certified that error appears in the printed specification of the above numbered patent requiring correction as follows: Page 1, line 56, for "low" read lower; page 3, line 76, claim 2, after "cellulosic" insert backing; and line 85, strike out the comma after "back"; and that the said Letters Patent should be read with these corrections therein that the same may conform to the record of the case in the Patent Office.

Signed and sealed this 25th day of September, A. D. 1934.

Leslie Frazer
